[57] CLAIM

The ornamental design for a handle for a fishing rod, as
shown and described.

DESCRIPTION

FIG. 1 is an elevational view of one side of a handle for
a fishing rod showing our new design;
FIG. 2 is a top plan view thereof.

FIG. 3 is a bottom plan view thereof.

FIG. 4 is a front elevational view thereof.

FIG. 5 is a rear elevational view thereof.

The broken line showing of the rod is for environmental
purposes only and forms no part of the claimed design.
